US00D924901S

(12) **United States Design Patent** (10) Patent No.: **US D924,901 S**
Garg et al. (45) Date of Patent: **** Jul. 13, 2021**

(54) **DISPLAY SCREEN OR PORTION THEREOF WITH GRAPHICAL USER INTERFACE**

(71) Applicant: **salesforce.com, inc.**, San Francisco, CA (US)

(72) Inventors: **Vandit Garg**, Antioch, CA (US); **Anthony Desportes**, San Francisco, CA (US); **Brian Truong**, San Francisco, CA (US); **James Matt Holland**, San Francisco, CA (US); **Lovish Agarwal**, San Francisco, CA (US); **Lisa Kaplan**, Piedmont, CA (US); **Melanie Krassel**, San Francisco, CA (US); **Yuan Wang**, Dublin, CA (US); **Bhupinder Johal**, Surrey (CA); **Wenying Yang**, San Francisco, CA (US); **Julia Wolinsky**, San Francisco, CA (US); **John Donohoe**, Oakland, CA (US); **Andy H Kung**, Belmont, CA (US)

(73) Assignee: **salesforce.com, inc.**, San Francisco, CA (US)

(**) Term: **15 Years**

(21) Appl. No.: **29/722,786**

(22) Filed: **Jan. 31, 2020**

(51) LOC (13) Cl. **14-04**

(52) U.S. Cl. **D14/485**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost dashed broken lines in the FIGURE show a display screen or portion thereof and form no part of the claimed design. The other dashed broken lines in the FIGURE show portions of the graphical user interface that form no part of the claimed design.

1 Claim, 1 Drawing Sheet
